METHOD OF AND MACHINE FOR OPERATING
UPON SOLESErastus E. Winkley, Lynn, Mass., assignor to
United Shoe Machinery Corporation, Paterson,
N. J., a corporation of New JerseyApplication December 20, 1928
Serial No. 327,339

73 Claims. (Cl. 12—17)

This invention relates to a process, and to a machine which operates in accordance with the process, for shaping unattached soles and is herein described as relating to treatment of the shank portions of soles by which they are readily conformed to the shape usually imparted thereto in the finished shoes.

Sole blanks are commonly died out of a hide, the size of each blank being governed by the requirements of the shoes of which it is to become a part. The sole blank may then be clamped by its fore and heel parts and stretched throughout the shank portion to elongate it; and, if it is desired, the stretching operation may be accompanied by an operation by which the marginal portions of the shank of the sole may be additionally stretched beyond the limit of their elastic recovery and to a greater extent than that to which the central portion of the shank has been stretched. The result of the above treatment is the production of a sole, longer than the blank from which it was made, having a shank portion formed substantially to the shape it will assume in the finished shoe. A more detailed description of these methods of treating soles and of apparatus for performing them may be obtained by reference to Letters Patent of the United States No. 1,552,608, granted on September 8, 1925, on application of Chester Hunt and Frederic E. Bertrand, Letters Patent No. 1,722,294, granted on July 30, 1929, on application of said Hunt and Bertrand, and Letters Patent No. 1,772,038, granted on August 5, 1930, on application of Herman Davenport and N. F. Hopkins.

On account of the variation in quality of soles—even of those cut from the same hide—it has been found that they occasionally emerge from a shank treating operation of the above-described sort with their edges cracked somewhat; and that the extension of the edges of the shank portion of a sole the shank of which is given a regular transverse curvature is often greater than the elasticity of the leather will permit without rupture.

It is therefore a general object of this invention to provide a new and improved method and apparatus for shaping the shanks of soles by the use of which the work may be finished more rapidly and with a smaller percentage of cripples than has heretofore been possible. In accordance with this object of the invention, an improved process and apparatus described and shown herein is provided for so treating the shanks of soles that excessive extension of their

edge portions so as to cause a rupture therein is avoided. To this end the process is carried out in a novel machine comprising means for stretching the shank portion of a sole by increasing amounts across part of the width of the shank and at either side of the central longitudinal axis and by substantially equal amounts outwardly across the remainder of the shank at either side of its longitudinal median axis.

In treating the shank of a sole in the above-described manner, a conforming tool is employed to force the shank portion of the sole against and about a cooperating member, herein termed a "pattern", the shank portion of which is transversely convex continuously between the fore and heel part sections. The shank portion of the pattern is bordered at either side by a relatively narrow surface which is substantially parallel to a surface tangent to the uppermost part of the shank portion of the pattern. It will become more apparent as the description of the invention proceeds that the stresses set up in the marginal portion of the shank as above treated are relieved sufficiently to eliminate the possibility of cracking by the support provided by the marginal surfaces of the pattern.

When, for economy of manufacture, the shanks of soles are appreciably extended so that a blank of one size may be used for the sole of a shoe of a larger size, it is apparent that the elongation of the shank portion is accompanied by a corresponding decrease in its width and hence by a change in the contour of the edges. Therefore, in contemplation of the change in shape of a shank upon its extension when subjected to a stretching operation, a special set of blanking dies for cutting soles from the hide will be required. It is also apparent that, in cutting sole blanks in relatively small lots, it would be impracticable to have special blanking dies constructed. Hence it is desirable in some instances to shape the shanks of the soles without appreciably elongating the shank portion. The operation of shaping the shanks of soles for men's shoes, in which the fore and heel parts of the sole are substantially in the same plane, without appreciably elongating the shank portion, ordinarily entails no great difficulty. Such soles may be shaped about a pattern the top surface of which is substantially straight from one extreme to the other. However, the heel parts of soles for use in women's shoes having high heels must be displaced relatively to the fore parts a distance substantially equal to the height of the heel, in order that they may fit

the lasted shoe and in order that the resilience of the soles will not tend to pull the shoes out of their intended shape; but, so far as applicant is aware, in the operation of machines for shaping soles the heel and fore parts of which are relatively displaced during the shaping operation, the displacement occurs in such a way that the fore and heel parts are separated proportionally as they are displaced, thereby 5 parting a corresponding extension to the shank between the fore and heel parts.

Accordingly, in another aspect the invention consists in providing a process of, and apparatus for, stretching the shank portion of a sole 10 lengthwise at either side of its central longitudinal axis to impart a transverse curvature thereto without stressing or stretching the axial portion lengthwise thereof, the fore part and heel part of the sole being disposed obliquely to 15 the shank and constrained against relative movement lengthwise of the sole. To this end the illustrated machine is provided with clamps for gripping the fore part and heel part of a sole and means for controlling the distance between 20 said clamps as they are relatively displaced to shape the shank and sole longitudinally. This means comprises apparatus so constructed and arranged that, upon displacement of the clamps so that the shank portion of the 25 sole is obliquely disposed to either or both the fore and heel part, the distance between the clamps may remain constant. Although, as above pointed out, the mechanism may thus be operated to shape the shank without bodily 30 extending it, the means for controlling the distance between the clamps as they are relatively displaced may also be adjusted to decrease the distance between the clamps as they are relatively displaced, and also to increase the distance 35 between the clamps to produce a result similar to that attained by use of the machine disclosed in the above-mentioned Davenport and Hopkins patent.

When the illustrated machine is used for operating upon soles for men's shoes in which there 40 is little longitudinal curvature, the conforming tool moves relatively to the pattern to shape the shank thereabout, in a direction substantially perpendicular thereto. It is apparent that in 45 such a case the conforming tool will naturally be seated squarely against the pattern. However, when the shank portion of the sole is disposed obliquely to the fore and heel parts, as is the case when soles for women's shoes are being 50 operated upon, the conforming tool approaches the shank of the sole and the corresponding part of the pattern in a direction which is oblique to the general direction of the shank 55 portions of the sole and pattern. In view of the desirability of having the conforming tool seat 60 squarely against the shank portions of the sole and pattern irrespective of their relative position, another object of the invention is to provide means for conforming the shank of the sole to the pattern constructed and arranged to 65 seat itself flatly on the shank irrespective of its direction of motion with respect to the shank and pattern during the conforming operation. 70 To this end the conforming tool comprises a work engaging element pivoted to the conforming tool body about two axes, thereby allowing the work engaging element of the conforming tool to be disposed squarely against the shank 75 portion of the sole and pattern, even though

they are disposed at an angle to the direction of motion of the conforming tool.

The illustrated machine in which the invention is embodied comprises two sets of operating instrumentalities for shaping soles constructed 80 and arranged to be operated so that, when one operating instrumentality is shaping the work, the other is in position to receive a blank and vice versa. Thus, it is apparent that the operator's time during the period when a sole is 85 being shaped would be wasted if only one set of instrumentalities were used, and that, by the provision of a machine having two sets of operating instrumentalities alternately effective to 90 shape the work, the output of a single operator is substantially increased.

In the illustrated machine, that element of the clamping mechanism which supports the pattern, and the cooperating clamping element, 95 are constructed and arranged for relative advance to clamp the work and for relative separation to facilitate placing the sole on the pattern. To facilitate placing the blank on that part of the clamping mechanism which supports the pattern, it is withdrawn relatively to the other clamping element from the position it occupies when clamping a sole by being swung forwardly and toward the operator. Thus, in its blank receiving position the pattern and the clamp which supports it are so disposed with 100 respect to the rest of the machine that a sole blank may be placed thereon in an unobstructed path the direction of which is perpendicular to the face of the clamp and the pattern.

Although, nominally, shoes of the same width 110 size but of different lengths are presumed to be of the same actual width and shoes of the same length size but of different widths are presumed to be of the same actual length as a matter of practice this is not true. In order that shoes of 115 the same style or class may be identified as such irrespective of their size, it is obvious that their general proportions must be substantially the same. Hence, as a matter of practice the soles of all sizes for the same style or class of shoes 120 are substantially geometrically similar and, therefore, as between soles of different sizes, the differences of length and the differences of width are substantially proportional.

Although different patterns are required for 125 classes of work which vary widely, it is desired that only one pattern be used for various sizes of soles of the same class. However, if one pattern is to be used for various sizes of soles of the same class, the soles must be so placed on 130 the pattern that their respective axes are substantially coincident and that their longitudinal centers are aligned. To facilitate positioning the soles on the pattern in this way and in accordance with another feature of the invention, 135 means adapted to contact with the sole edge at an end and side thereof is provided in the illustrated machine by one rectilinear adjustment of which the position of soles on the pattern are accurately limited both longitudinally 140 and widthwise of the pattern. This means comprises a gage mechanism for positioning the sole properly on the pattern which is mounted for movement in a direction oblique to the longitudinal axis of the sole and pattern and is positioned upon movement of the part of the clamping means which supports the pattern to its sole receiving position.

Since the length and width of various sizes 145 of soles of the same style vary proportionately 150

between different sizes as it has been pointed out above the gage mechanism may be operated to gage a sole both longitudinally and width-wise of the pattern by one movement if the direction of this movement of the gaging element is at such an angle to the longitudinal axis of the sole that the tangent of the angle is equal to the ratio of the increase in width to the increase of length between successive sizes of soles. It may thus be seen that a gage mechanism so constructed and adjusted will compensate for the length extension accompanying corresponding width extensions of soles simultaneously.

15 These and other features of the invention, including various novel constructions and arrangements of parts, will appear more fully from the following description when read in connection with the accompanying drawings and will 20 be pointed out in the appended claims.

In the drawings,

Fig. 1 is a front elevation showing the machine with certain parts broken away for clearness of illustration;

25 Fig. 2 is a central vertical section along the line II—II of Fig. 1;

Fig. 3 is a side elevation, with parts in section, of the clamping mechanism for operating the heel part clamp and driving mechanism therefor;

30 Fig. 4 is a side elevation of the fore part clamping mechanism, showing also the manner in which it is mounted in the frame;

Fig. 5 is a sectional plan view taken along the 35 line V—V of Fig. 4 and illustrates the mechanism for providing a parallel motion for the fore part clamping mechanism;

Fig. 6 is a side elevation of a work clamping mechanism oscillated to its blank receiving position and operating means therefor;

40 Fig. 7 is a side elevational view, partly in section, of the clamping mechanism, showing mechanism for displacing the heel part clamp with respect to the fore part clamp;

45 Fig. 8 is a front elevation of one of the work clamps and the conforming tool shown in the positions occupied immediately after a conforming operation has been performed on a sole for a woman's shoe;

50 Fig. 9 is a perspective view of the pattern used for shaping soles for women's shoes;

Fig. 10 is a side elevational view showing the conforming tool with driving means therefor and a cooperating work clamp and pattern of 55 the type used for operating on soles for men's shoes;

Fig. 11 is a front elevational view showing the relation of the parts of the conforming tool when it is in its lowermost position when operating upon soles for women's shoes;

60 Fig. 12 is a sectional view along the line XII—XII of Fig. 1 showing a conforming tool cooperating with an improved form of pattern;

Fig. 13 is a perspective view of a gage mechanism used in connection with the fore part clamp;

Fig. 14 shows in perspective a form of pattern and conforming tool for shaping soles for men's shoes;

70 Fig. 15 illustrates an arrangement of scales from which the gages are adjusted;

Fig. 16 is a plan view of a modification of the scale arrangement shown in Fig. 15; and

75 Fig. 17 is a perspective view of an additional scale arrangement.

The illustrated machine for conforming the shank portions of unattached soles described herein comprises two sets of operating instrumentalities, only one of which has been fully illustrated in Fig. 1. Unless otherwise noted, it is to be understood in connection with the description which is to follow that all parts referred to, excepting the frame elements and certain parts of the driving mechanism, occur in duplicate and are geometrically similarly placed in the machine.

80 In operating on soles for men's shoes, a pattern 20 such as shown in Fig. 1 is used, the fore and heel parts of which are supported by clamp tables 22 and 24, respectively. The pattern 20 is held in position on the clamp tables 22 and 24 by dowels 26 (Figs. 2 and 3), firmly seated in the clamp tables and extending into complementary recesses in the bottom of the pattern. Integral

85 with and extending downwardly from the heel part clamp table 24 are legs 28 and 30 (Fig. 1) at the lower ends of which they are supported by a pin 32 (Figs. 2 and 3) fixed at the top of a support 34. The support 34 is fixed to a guide

90 rod 36 which is arranged for axial movement, being supported at its upper end by a bearing 38 extending at either side from the central web 40 of the upper frame 42 of the machine. At its lower end the guide rod is slidably engaged in a complementary hole 44 in the lower panel

95 46 of the upper frame 42. The support 34 may be held stationary or reciprocated axially by a mechanism to be later described. A pair of levers 48, one at each side of the support 34,

are pivoted to the pin 32 at one end and at the 100 other to a pin 56 to which is also pivotally connected the lower link 52 of a toggle 52—54. The upper end of the toggle link 54 is pivoted to a clamp jaw 56 by a pin 58 fixed in the upper

105 end of the clamp jaw which is held relatively 110 fixed to a guide rod 60 mounted for axial reciprocation at its upper end in a bearing 62 in the head 64 of the upper frame 42 and at its lower end in a bearing 76 in the lower panel 46. The levers 48 are fulcrumed between their ends

115 120 on a trunnion block 66 mounted to slide on the guide rod 60 and resting on a helical spring 68 surrounding the guide rod 60.

To the joint of the toggle 52—54 is pivotally connected an adjustable connecting rod 94 pivoted at its other end to one end of a lever 96 rotatably mounted on a shaft 108 which is supported at both ends and at the center by the upper frame 42, as shown in Fig. 1. To the

120 lower end of the lever 96 is attached a rod 98 connecting it with another similar lever 100 (Fig. 4) also pivoted on the shaft 108 and connected to a toggle 102—104 by a connecting rod 106 for operating the fore part clamping mechanism. The toggles 52—54 and 102—104 are

125 straightened and broken through their respective connecting rods and clamp levers by an oscillating bell crank 110 (Fig. 3) pinned to a shaft 112 which is rotatably supported at each

130 end in bearings 114 (Fig. 1) in the upper part 140 of a lower frame 116. The arm 118 (Fig. 3) of the bell crank lever 110 remote from the clamping levers carries at its outer extremity a roll 120 rotatably mounted on a stud 122 fixed to the arm 118. The roll 120 engages a cam track

145 124 in a cam 126 which is keyed to a shaft 128 rotatably mounted in bearings 130 at each side of the lower frame 116. Only one cam 124 is included in the machine for operating the clamping mechanism in both operating instrumen-

talities each of which comprises a bell-crank driven from the common shaft 112 for operating their respective clamping mechanisms.

The helical spring 68 is supported by a sleeve 70 (Fig. 3) which may be adjusted longitudinally along the guide rod 60 by means of a nut 72 threaded on the end of the guide rod 60. The nut 72 is provided at its lower end with a series of perforations 74 into which an implement may be inserted to facilitate the adjustment of the position of the sleeve 70 along the guide rod 60 and hence the compression of the spring 68. In order that the heel part clamp jaw 56 shall not rotate with respect to the frame, it is provided at its lower end with a bifurcated bracket 78 which surrounds the guide rod 36, which is mounted only for axial movement. The bracket 78 by engagement with the rod 36 prevents the clamp jaw 56 on the guide rod 60 from rotating in either direction from its desired position.

The heel part clamp jaw 56 and a fore part clamp jaw 80 are provided with face blocks 82, 84, (Fig. 1) respectively, which are slidably held upon the lower clamping faces of the clamp jaws 56 and 80, respectively, by T-shaped, dovetailed connections 86. The clamp face blocks are held on the clamp jaws by buttons 88 pivotally mounted thereon and which may be swung downwardly to prevent the face blocks from being removed, or swung upwardly, to allow the clamp faces to be pulled off the dovetailed connections 86. A strip of rubber or other resilient material 90 is secured to the opposite extremes of the clamp face blocks and is stretched therebetween to provide a gripping and non-marring work engaging face for the clamp jaws.

The marginal portions of the fore and heel part clamp tables are provided with channels 91 which collect whatever fluid may be squeezed from tempered soles when they are subjected to clamping pressure. The fluid is conducted from the channel in the fore part clamp table by means of a tube 93 (Fig. 4) the lower end of which is fastened to one side of an arm 226 and terminates slightly above the bottom panel 46 of the upper frame 4. Similarly, the tube 95 (Fig. 2) delivers the fluid collected by the heel part clamp table to the bottom panel 46. As shown in Fig. 2, the bottom panel is dished and is provided at the lowest portion thereof with a drain comprising a pipe 97 which is tapped into the bottom panel and which terminates at its other end slightly above the bottom panel of the lower frame 116. The bottom panel of the lower frame is also dished, thereby insuring that the fluid delivered by the pipe 97 will be collected at one spot in the base of the machine away from the operating parts thereof.

The shaft 128 is driven by a gear 132 (Fig. 1) which is keyed thereto and which, in turn, is driven by a gear 134 which is fixed to a sleeve 136 (Figs. 1 and 3) rotatably mounted on a shaft 138 fixedly supported in bearings 140 at the ends of the lower frame 116 and at the middle by a bearing 142 which is supported by a web 144 integral with the bottom panel 146 of the lower frame. The sleeve 136 may be engaged with and disengaged from a gear 148, freely rotatable about the shaft 138, by a clutch mechanism 150. A counter-shaft 152 carries at one end a pinion 154 which meshes with the clutch gear 148 and carries at the other end

another gear 156. The shaft 152 is mounted for rotation in bearings 153 one of which is in one side of the lower frame and the other of which is integral with the central web 144 supported by the bottom panel of the lower frame. Extending inwardly from the right-hand side of the frame as seen in Fig. 1, is a bearing 158 which rotatably supports a drive shaft 160 (Fig. 3) having pinned at the inner end thereof a pinion 162 which meshes with the gear 156. The shaft 160 at its outer end may be connected to a source of power by any suitable means. The above-described gearing, together with a clutch mechanism to be described, constitutes a speed reduction drive and means whereby only one revolution of the shaft 128 carrying the cam which operates the clamping mechanism will result from a single actuation of the treadle, as will presently be described.

Springs 164, when permitted to do so, urge the clutch element 150 to the right as shown in Fig. 1, thereby effecting a driving connection between the gear 148 and the sleeve 136. The clutch element 150 is released so that the springs 164 may operate to establish a driving connection, as above stated, by depression of a treadle 166 which is pivoted to a stud 168 fixed in the web 144. The treadle 166 is, in effect, a bell crank, and pivotally connected to the upright arm 170 thereof is a connecting rod 172 (Figs. 1 and 2). The connecting rod is pivotally attached to a catch 174 having a notched lower end 176 which engages the upper surface of the flattened end 178 of a T-shaped bell crank 180. The upstanding arm of the bell crank 180 has an end comprising two forks 182 (Fig. 2) each of which pivotally supports a sector 184 which is received within a peripheral groove 186 of the clutch element. The upper end of the catch 174 is pivoted at 188 to a lever 190 which is rotatably mounted on a shaft 192 rotatably mounted in bearings 194 at each side of the lower frame. A roll 196 is mounted on the end of the arm 190 and is adapted to engage the surface of a cam 198 which is keyed to the shaft 128, which has been described as supporting the cam 126 for driving the clamping mechanism. When the treadle 166 is depressed, the lower end of the catch 174 is pulled off the end 178 of the left-hand arm of the bell crank 180, thereby releasing it and allowing the springs 164 to force the clutch element 150 to the right as seen in Fig. 1, and to effect a driving connection between the gear 148 and the sleeve 136. The shaft 128 is thus caused to rotate, driving the cam 126 to operate the clamping mechanism. As a full revolution of the shaft 128 is about to be completed, the roll 196 on the lever 190 which is held against the face of the cam 198 by a spring 199 fixed to the lever 190, rises into the recess in the cam, thereby lifting the catch 174. When the catch 174 is thus lifted to its highest position, its notched end 176 again engages the flattened end 178 of the left-hand arm of the bell crank 180 and, upon further rotation of the shaft 128 and hence the cam 198, the latter imparts a counterclockwise rotation to the lever 190 as the roll 196 rides out of the cam recess, thereby pushing the catch 174 downwardly and the upstanding arm 180 of the bell crank in a counterclockwise direction (Fig. 1) to disengage the clutch. The friction between the moving parts of the machine is sufficient to stop it immediately upon disengagement of the clutch.

It is desirable frequently to be able to stop the

machine at any stage of its operation. To this end the machine is provided with a treadle 200 pivoted at 202 to an upstanding lug 204 integral with the bottom panel of the lower frame 116. 5 The inner end 206 of the treadle 200 engages the end of the right-hand arm 208 of the bell crank lever 180. It is apparent, then, that at any stage of the operation of the machine it may be stopped by the depression of the treadle 200, 10 which causes the upstanding arm 180 of the bell crank to be rotated in a counterclockwise direction, thereby disengaging the clutch. Simultaneously the left-hand arm of the bell crank lever is lowered and again becomes engaged beneath the notched end of the catch 174 which must be released again before the operation of the machine can be resumed. Springs 209 sufficiently strong to counteract the weight of the treadles tend to hold them in their uppermost 15 position.

Having described the apparatus for giving one revolution for each depression of the treadle to the main drive shaft 128 and the cam 126, the operation of the clamping mechanism driven by this cam will next be described. Upon each 25 full revolution of the cam 126 the bell crank 110 moves from the position in which it is shown in Fig. 2 to that shown in Fig. 3 and back again, thereby straightening and breaking the toggles 52—54 and 102—104. During the movement of the lower link 52 of the heel part toggle mechanism to its straightened position, the levers 48 are rotated about their fulcrum on the trunnion block 66, thereby raising the pin 32 and therefore the clamp table 24. The parts 30 of the clamping mechanism are so proportioned that when the clamp is closed firmly to hold the work the trunnion block 66 is displaced slightly against the pressure of the spring 68. It may therefore be seen that the clamping pressure 35 may be regulated by the adjustment of the nut 72 on the lower end of the guide rod 60 and that a variation in the thickness of the work will not cause the clamping mechanism to be any the less effective.

The fore part clamping mechanism operates in much the same manner as the heel part clamping mechanism which has just been described. The oscillation of the bell crank 110 imparts a similar oscillation to the clamping lever 100 (Fig. 4) which, through the connecting rod 106, operates the toggle 102—104 to close and separate the fore part clamp jaw 80 and clamp table 22. When the toggle 102—55 104 is straightened, levers 210, one at each side of a guide rod 212 which alines the fore part clamping mechanism vertically, are rotated in a clockwise direction with respect to a sliding trunnion block 214 mounted on the guide rod 212 and about a pin 216 which pivotally connects the outer ends of the levers 210 and the legs of the fore part clamping table 218, thus bringing the clamping elements into engagement with the work. The guide rod for the fore part clamping mechanism is also surrounded by a helical spring 220 the compression of which exerted against the sliding trunnion block 214 may be adjusted by rotating a nut 222 which is threaded to the lower end of the 60 guide rod 212 and bears against the lower end of the spring 220. The nut 222 is also perforated at its lower end to receive an implement to facilitate its adjustment, as shown in Fig. 4. The fore part clamping mechanism is 70 supported by the pin 216 which is carried by a

yoke 224 rotatably supported in an arm 226 which is integral with a sleeve 228 supported by a rod 230 bearing at each end in the upper frame. The parts of the fore part clamping mechanism are also so proportioned that when a sole is clamped therebetween the trunnion block 214 is slightly separated from the lower end of the clamp jaw 80 to compress the spring 220, thereby providing a resilient clamping pressure for the fore part of the sole.

When the illustrated machine is being used for shaping soles for men's shoes, in which case a pattern similar to that shown in Figs. 1 and 10 or that in Fig. 14 is used, the fore part and heel part clamp tables are operated simultaneously and in the same way. As soon as the clamp tables have been operated firmly to clamp the sole, the conforming tool is operated to shape the shank of the sole about the pattern.

As illustrated in Figs. 1 and 10, the conforming tool comprises a shank 232 slidably supported in a bearing 234 in the head 64 of the upper frame. The conforming tool shank 232 is provided at its lower extremity with a dovetailed groove 236 of T-cross-section. A slide 238 (Figs. 100 10 and 14) is constructed to fit the groove 236 and carries a shield 240 in which a resilient work engaging element 242 is retained. The work engaging element 242 may be adjusted widthwise of the pattern 20 by rotation of a 105 screw 244 between the threads of which a lug 246 on the slide 238 is engaged. The screw 244 may be turned by a thumb lever 248 which also provides a closure for the recess in which the screw is seated. A spring-pressed plunger 110 250 is adapted to engage any of a series of recesses in the back surface of the screw to hold it in any desired position of adjustment. A slot 251 extending longitudinally of the screw allows the slide 238 to be removed readily when 115 the screw is turned to align the slot and the lug 246. Movement is imparted to the conforming tool through a lever 252 both ends of which are forked. At one end it is pivoted on a pin 254 to the shank of the conforming tool and 120 at the other end is fulcrumed by a pin 256 to the lower end of a link 258 pivotally mounted on a pin 260 in the head 64 of the upper frame 42. A clevis 262 is pivoted on the pin 264 to the mid portion of the lever 252. A connecting 125 rod 266 is threaded at one end into the lower end of the clevis 262 and held in the desired position by a check nut 268. A block 270 is threaded to the lower end of the rod 266 and is prevented from rotation with respect thereto 130 by a check nut 272. The connecting rod 266, and hence the conforming tool, is operated by an oscillating arm 274 carrying a roll 276 rotatably mounted on a stud 278 fixed to the arm 274. The roll 276 is received within a track 135 280 in a cam 282 which is keyed to the main drive shaft 128. In order that the effective throw of the cam may be varied, the lower end of the connecting rod 266 may be adjusted with respect to the arm 274. To this end the block 140 270 is pivotally mounted on a cross-head 284 which is slidably and adjustably received in an arcuate slot 286 in the arm 274. In order that the cross-head 284 may be moved into any position in the slot 286, it rotatably supports 145 a nut 288 into which is threaded an adjusting screw 290 having on its outer end a hand-wheel 292 by which it may be turned to move the cross-head 284 to any desired position. The screw 290 is prevented from moving axially by 150

cooperating shoulders 294 and 296 on the screw and hand-wheel respectively. These shoulders abut opposite sides of a pin 298 rotatably mounted in the outer end of an extension 300 of the arm 274. By means of the above-described mechanism the conforming tool may be given one complete reciprocation from its upper position, as shown in Fig. 1, downwardly, until it has forced the shank portion of the sole firmly against and about the corresponding part of the pattern, and back again to the retracted position upon one revolution of the cam 282. This movement of the conforming tool occurs during the time when the sole is held firmly gripped by the clamping mechanism. As soon as the conforming tool has been retracted, the conforming operation having been completed, the clamping mechanism is operated to release the sole, and the fore and heel part clamp tables are relatively separated from the corresponding clamp jaws; thereafter the fore and heel part clamp tables carrying the pattern are rotated forwardly, as shown at the right in Fig. 1, about the pins 216 and 32, respectively, in order to facilitate the operation of removing the conformed sole from the pattern and placing a blank to be operated upon in the machine.

The means for swinging the clamp tables to the blank receiving position comprises a double armed bell crank, one arm 302 (Fig. 6) of which carries a laterally extending pin 306 adapted for engagement within an elongated slot 304 in the leg 30 of the heel part clamp table. By means of a yoke 310 the arm 302 is connected to an arm 308 which has at its upper end an elongated slot 312. A rod 314 extends through the slot 312 in the arm 308 of the bell crank and is prevented from axial movement with respect to the arm 308 by collars 316 (Fig. 1). The fore part clamp table 22 is slidably mounted, for reasons to be explained hereinafter, on the rod 314. Also effectually integral with the arms 302 and 308 is an arm 318 to which is pivoted at its outer end a rod 319 having a clevis 320 adjustably fixed to its lower end. The clevis is pivoted at 322 to one arm 324 of a bell crank which is rotatably supported by the rod 192 journaled at each end in the bearings 194 (Fig. 1) in the sides of the lower frame. The other arm 326 of the bell crank carries at its outer end a roll 328 rotatably mounted on a stud 330 fixed to the end of the arm 326. The roll 328 is engaged in a track 332 of a cam 334 which is fixed to a sleeve 336 (Fig. 1). The sleeve 336 is rotatably mounted on the shaft 138 and is driven by a pinion 340 on the end of the shaft 128 through an idler gear 342 which meshes with both the gears 340 and 338. The idler 342 is rotatably mounted on a stud shaft 344 (Fig. 2) fixed in the left-hand side of the lower frame as seen in Fig. 1. A cam 335 identical to the cam 334 is keyed to the sleeve 336 but is rotated through an angle of 180 degrees with respect to cam 334. The work clamping tables of the operating instrumentality partially shown at the right in Fig. 1 are oscillated by means of the cam 335 through an arm 337 one end of which engages the cam track of the cam 335 and the other of which is pinned to the shaft 192. An arm 339 is also pinned to the shaft 192 and is connected to the clamping table mechanism of the partially illustrated operating instrumentality by the connecting rod 341.

When the operation of the machine is stopped by the one-revolution clutch mechanism, one

pair of the clamp tables carrying the pattern are in blank receiving position, as illustrated in Fig. 6. When the machine is next started, the cam 334 moves the bell crank 324 in a counter-clockwise direction, thereby rocking the arms 302 and 308 in a clockwise direction. By means of the connections above described, the clamp tables are therefore moved to the position in which they are shown in Fig. 2 when the work clamping operation is about to be started.

The above description refers to one set of instrumentalities for operating upon soles for men's shoes but, as stated above, the illustrated machine provides two sets of instrumentalities for performing the shank shaping operation, the coordination of which will be more fully described later.

When soles for women's shoes are to be operated upon, in which case the heel parts of the soles are to be displaced appreciably with respect to the fore parts, a pattern such as that shown in Fig. 9 is used. The shank portion 346 is pivotally attached, by means of a pin 348, to the fore part of the pattern which is supported by the fore part clamp table 22 and is alined thereon by means of the dowel 26 engaging a recess in its lower face as above described in connection with the pattern for use in operating upon soles for men's shoes. The heel part 352 of the pattern is located in a similar manner upon the heel part clamp table and is provided at one end with a recess 354 into which extends the reduced end 356 of the shank portion of the pattern which is supported by the upper face of the heel part clamp table. When a blank 110 is presented to the machine to which the pattern shown in Fig. 9 is attached, the faces of its fore and heel part portions are substantially in the same plane. This relation is maintained while the clamp tables are swung to the clamp- 115 ing position from blank receiving position and until the sole blank has been firmly gripped by the clamping mechanism. However, as soon as the sole blank has been gripped, the heel part clamp table and the corresponding clamp 120 jaw are bodily dropped a distance substantially equal to the height of the heel of the shoe for which the sole is intended. Simultaneously with the lowering of the heel part clamping mechanism, the conforming tool is also reciprocated 125 downwardly but at a greater rate than the movement of the heel part clamping mechanism, so that when the heel part clamping mechanism has reached its lowest position, the conforming tool also has reached its lowest position and the 130 sole blank is pressed firmly against and about the shank portion of the pattern.

As has been stated above, the fore and heel part clamping mechanisms are so constructed and arranged that upon their relative displacement to dispose the shank portion obliquely to the heel and fore part portions the distance therebetween may be increased, decreased or held constant. In order that the distance between the fore and heel part clamp mechanism 140 may be varied, and in view of the fact that, as above described, the heel part clamping mechanism is capable only of a vertical reciprocation, it is necessary that the fore part clamping mechanism be capable of being displaced laterally relatively to the heel part clamping mechanism. Also, in order that the sole blank shall not be distorted during the relative lateral movement of the clamping mechanisms, it is necessary that the clamping mechanisms be main- 145

tained substantially in longitudinal alinement throughout the range of their adjustability. To provide for relative displacement of the clamping mechanisms longitudinally of the sole, the 5 guide rod 212 (Fig. 4) which supports the fore part clamping mechanism is rotatably mounted at its upper end in an arm 358 and at its lower end in the yoke 224 which is rotatably supported in the arm 226. The arms 358 and 226 are integral with the sleeve 228 which is rotatably mounted on the rod 230. The fore part clamping mechanism, being rotatable about the rod 230 as an axis, may therefore be adjusted longitudinally of the sole with respect to the heel 10 part clamping mechanism. In order accurately to control the distance between the two clamping mechanisms, additional means is provided for adjustably limiting the distance between the clamping mechanisms and which also determines 15 the extent of their separation when in the position of their greatest relative displacement. This means comprises a connecting link 360 (Fig. 1) which is attached to both the heel and the fore part clamping mechanisms. The 20 connecting link 360 is attached to the heel part mechanism through a universal joint 362 which may be adjustably secured by means of a bolt 364 in any position in an arcuate slot 366 in a bracket 368 which is secured to the clamping 25 jaw of the heel part mechanism by bolts 370. At its other end the connecting link 360 is attached to a slide 372 by means of another universal joint 374. By turning a screw 376 the fore part clamping mechanism, having at its upper end a 30 slideway 378, is moved relatively to the slide 372, thereby adjusting the distance between the fore and heel part clamping mechanisms.

If it is desired to elongate the shank of the sole upon relative displacement of the fore and heel part clamps, the universal connection 362 of the connecting link 360 is clamped to the bracket 368 in the upper part of the arcuate slot 366. When the heel part clamp is lowered with the connecting link thus adjusted, the fore 40 part clamp is moved away from the heel part clamp, since the connecting link, by such a motion, is brought toward a horizontal position in which the heel and fore part clamps are separated by the greatest distance for any one 45 adjustment of the fore part clamp with respect to the slide 37. If it is desired that the shank of the sole shall not be stretched, the connecting link 360 is adjusted to substantially the position 50 in which it is shown in Fig. 1. If, however, it is desired to diminish the distance between the fore 55 and heel part clamps upon their relative displacement, the link 360 may be adjusted so that the universal connection 362 is clamped at the lower part of the slot 366, as illustrated 60 in Fig. 8. When the heel part clamping mechanism is lowered, thereby moving the fore part clamping mechanism by means of the connecting link 360, the fore part clamping mechanism moves longitudinally of the sole about the guide 65 230 as above described.

To insure the substantial alinement longitudinally of the sole of the fore and heel part clamping mechanisms during their relative displacement, the yoke 224, a part of the fore part 70 clamping mechanism, is provided with a lug 380 (Fig. 5) to the outer end of which a link 382 is pivoted by means of a bolt 384. At a distance from the center of the bolt 384 equal to that between the center of the guide rod 230 75 and the center of the guide rod 212, the link

382 is bored to receive a stub shaft 386 spaced from the guide rod 230 a distance equal to the distance between the center of the guide rod 212 and the center of the bolt 384. Therefore, upon a rotation of the sleeve 228 carrying therewith the arms 358 and 226, successive positions of the yoke 224 are mutually parallel and therefore successive positions of a line between any two points on the yoke are mutually parallel. The yoke 224 supports a pin 388 which extends between the sides of a bifurcated lug 390 extending laterally from the lower end of the fore part clamping jaw 80. Since a line between the center of the pin 388 and the center of the shaft 212 assumes positions which are mutually parallel upon rotation of the sleeve 228, it is apparent that similar successive positions of the clamp jaw will likewise be in a parallel relation. The forward end of the yoke 224 is bifurcated and between the bifurcations 392 is disposed the lever 100 which is moved along its support 103 as the fore part clamping mechanism is moved.

The mechanism for dropping the heel part clamping mechanism comprises a lever 394 (Fig. 7) which is pivoted to the support 34 by means of the pin 396. An arm 398 is pivoted to the rod 112 and provides an adjustable fulcrum at its upper end for the lever 394 the end of which remote from the support 34 is pivotally connected by a pin 400 to a link 402 which is pivoted to another link 404 by a pin 406, mounted in the end of which is a roll for engaging a track 408 in a cam 410. The link 404 is pivoted also to the shaft 112, thereby restraining the movement of the roll engaged by the cam track 408 in an arcuate path about the shaft 112 as a center. It is apparent that upon rotation of the cam 410 which is driven by the shaft 128 that the lever 394 will be oscillated about the end of the arm 398 as a fulcrum, thereby reciprocating the support 34 and hence the entire heel part clamping mechanism. It may be noted that during a reciprocation of the heel part clamping mechanism, which occurs, of course, while the sole is clamped, the adjustable connecting rod 94 will be rotated about its pivotal connection to the end of the clamping lever 96, thereby operating the toggle to a slight extent. This movement of the toggle is insufficient to relieve substantially the tension of the spring 68 or to bring the sliding trunnion 66 into engagement with the bottom end of the heel clamp jaw 56. It is apparent, therefore, that the dropping of the heel part clamping mechanism does not affect the gripping of a sole blank. In order to vary the distance by which the heel part mechanism is lowered or dropped, the fulcrum for the lever 394 is adjustable as above stated. To provide this adjustment, a screw 412 is threaded into a pin 414 rotatably supported in the fulcrum arm 398 and is also journaled in a bearing 416 rotatably mounted in the web 40 of the upper frame of the machine. The inner end of the hub of a hand-wheel 418, which is pinned to the screw 412, prevents axial displacement of the screw with respect to the bearing 416 in one direction while a collar 420 prevents axial displacement of the screw 412 with respect to the bearing 416 in the opposite direction. It is apparent from Figs. 2 and 7 that by turning the hand-wheel 418 and hence the screw 412 the fulcrum arm 398 may be moved from one of its extreme positions, as shown in Fig. 2, in a clockwise direction until the effective fulcrum is coincident with the axis of the pin 396 and in which

position the lever 394 may be oscillated without imparting any movement whatever to the heel part clamping mechanism which, under these circumstances, is in vertical alinement with the fore part clamping mechanism. This mechanism is so adjusted when patterns such as those illustrated in Figs. 1 and 14 are used.

For convenience in manufacture the illustrated machine has been so designed that only one cam for operating the clamping mechanism of both instrumentalities and one cam for operating the heel part lowering mechanism of both instrumentalities are required; but structural characteristics of the machine forbid the use of only one cam for operating the conforming mechanisms. However, in order that the length of stroke of both conforming tools may be adjusted simultaneously and to the same extent, sprockets 297 are provided on the hand-wheels 292 of the conforming tool adjusting mechanism which are mutually driven by a chain 299 running between them. As above stated, the cams for operating the clamping table oscillating mechanism are identical but relatively rotated by 180 degrees upon their driving shaft, but the cams on the shaft 128 are designed to provide a complete cycle of events upon a full revolution. Therefore, in order properly to synchronize the clamping, conforming, and table oscillating movements, the sleeve 336 carrying the cams 334 and 335, corresponding events of which are separated by 180 degrees, must be driven at one half the speed of the shaft 128. This speed ratio is secured through the gears 340 and 338, the gear 340 being one half the diameter of the gear 338. It is now apparent that for each revolution of the shaft 128 the clamping and conforming mechanisms are operated through a complete cycle, but only one operating instrumentality at a time is effective to clamp and shape the work and it is that instrumentality the work clamping tables of which have been oscillated to a vertical position such as that shown in Fig. 2 that is operative. While the work clamping tables of that instrumentality the parts of which are in work receiving position are oscillated forwardly, as shown at the right of Fig. 1 and indicated in Fig. 6, the work clamping and conforming mechanisms of that same instrumentality are being operated, but since the work clamping tables are now located out of the path of the conforming tool and the corresponding work clamping jaws, the last-mentioned elements merely go through their movements idly. Thus successive rotations of the clamping, conforming and heel lowering cams alternately operate the instrumentalities effectively to act on the work.

In order that the conforming tool shall abut the shank portion of the sole squarely, even though the sole shank has been disposed obliquely to the direction of motion of the conforming tool by the relative displacement of the clamping mechanisms, it may be constructed substantially as shown in Fig. 11, illustrating a preferred construction of this type. A shield 422 is adapted to retain a resilient work engaging element 424 and is retained in a plate 426 by a T-slot connection 428 allowing lateral adjustment of the shield and work engaging element. Pivoted to one end of the plate 426 by means of a pin 430 is a link 432 which may be received in a recess in the body portion 434 of the conforming tool 436. The body portion 434 is mounted for limited lateral swinging move-

ment on a stud 437 which allows the element 424 to seat itself squarely against the work laterally. The link 432 is also pivoted by means of a pin 438 to the lower extreme of the conforming tool. A helical spring 440 is connected at one end to the plate 426 and at its other end to the body 434 of the conforming tool normally to rock the plate 426 about an abutment 442 until a hook 444, the lower end of which surrounds the pin 430, engages a stop 446 in the conforming tool. In this position the work engaging element of the conforming tool is substantially horizontal. It is apparent from an inspection of Fig. 11 that the link 432 may be rotated in a counterclockwise direction until its top abuts the under surface of the shank of the conforming tool. This rotation will permit the work engaging face of the conforming tool to assume an oblique position, as it engages the sole, corresponding to the inclination of the shank of the sole being operated upon. If, however, the inclination of the shank portion of the sole being operated upon is greater than the rotation of the link 432 alone will compensate for, the plates 426, and hence the work engaging element, may be further rotated about the pin 430 in order that the conforming tool may abut the shank of the sole squarely irrespective of the extent of its inclination to the fore and heel parts.

The illustrated machine is provided with a pattern, as above described, for use in operating upon soles for women's shoes the shank portions of which must have a relatively pronounced transverse curvature. The shank portion of the pattern is also constructed so that each marginal portion of the shank is stretched substantially uniformly across its width and so that successive increments of width of the shank at either side of its center are stretched by increasing amounts. To this end the pattern, as furnished for the operation of shaping the shanks of women's soles, is provided with a shank portion 346 having a face continuously convex transversely thereof between the fore and heel part clamp portions (Figs. 9 and 12). Bordering each side of the convex work engaging face of the shank portion of the pattern is a shoulder 448 the vertical projection of which (Fig. 9) is substantially parallel to that of the uppermost face 120 of the shank portion of the pattern 346. It will be apparent from Fig. 9 that the shank of the sole held firmly about the pattern will be uniformly curved about the central portion of the pattern, and that the marginal portions of the shank will be curved in a reverse direction and will take the approximate direction of the shoulders 448. Thus, if the heel and fore part clamping mechanisms are so adjusted that, as they are displaced, the distance therebetween is not increased, the axial portion of the shank of the sole receives no stretching but the shank is stretched by increasing amounts at each side of its axis up to those portions which abut the shoulders 448 on the shank pattern 346. From the inner boundary of the marginal portion of the shank to its outer edge the shank is stretched by substantially equal amounts, since successive increments of width of the marginal portions have been displaced equal amounts from their original position in alinement with the fore and heel parts of the sole blank.

It is, of course, desirable that the machine be so constructed that a small number of patterns will serve for all sizes and classes of work.

Changes in the style of shoes are made largely by varying the proportions of only the fore part, although such changes may be accompanied by relatively slighter changes in the shank portion. 5 These changes may comprise either a variation in the contour of the edges or a change in the general direction of the shank with respect to the fore part, or a combination of both. However the variations are made, they are but slight 10 in the shank, and since only the shank portion of the sole is operated upon in the illustrated machine, if the respective shank portions of the pattern and soles can be accurately alined both lengthwise and widthwise thereof irrespective of 15 their size and style, the same pattern will serve a relatively wide variety of soles. To this end the illustrated machine is provided with a gage mechanism to assist in accurately positioning the sole blanks on the pattern. By the use of a gage 20 mechanism such as is disclosed herein it has been found necessary to have only one pattern for each class of work, the gage mechanism being so constructed and arranged that soles of the same class irrespective of their size will be so placed 25 on the pattern that their respective shank portions are in alinement both longitudinally and widthwise thereof. The heel parts of soles for women's shoes having wood heels do not have the same contour as the attaching face of the 30 heel but are cut straight across at the back for the sake of economy in producing the sole, since it is undesirable and, in fact, unnecessary that the sole be visible throughout its length. Such soles, when operated upon in the present machine, are gaged longitudinally at the toe portion 35 by a finger 450 (Fig. 13) which is pivotally mounted on a pin 452 carried by an extension 454 of the body 456 of a gage. Another pin 458 fixed to the extension 454 supports the finger 450 slightly above the fore part pattern 350. The 40 sole is gaged widthwise of the pattern by means of an abutment comprising a piece of resilient tubing 460 through which are inserted two wire loops 462 fixed to bolts 464 and 466 which are carried by a block 468. The loops 462 are bent 45 resiliently to stretch the tubing 460 vertically, as shown in Fig. 13, and also are collapsible so as not to interfere with the clamping elements when they are brought together, and to prevent the 50 gage abutment from being firmly gripped by the clamping elements. The block 468 may be adjusted perpendicularly to the axis of the sole blank by means of a set screw 470 which is received in a slot 472 in the block 468 and which is threaded into a place 474. In order to facilitate the removal of the pattern from the face of the clamp table, both the finger 450 and the abutment 460 may be rotated backwardly. This 55 rotation is provided for in the case of the abutment 460 by mounting the plate 474 pivotally on a pin 476 fixed to the body 456. A helical spring 478 surrounding the rod and abutting its outer end normally urges the plate 474 so that one end is received in a recess 480 in the body 456, thereby locking the plate in its operative position. However, if it is desired to rotate the abutment 460 so that the pattern may be readily removed from the clamping table, it is necessary 60 only to move the plate 474 to the right, as shown in Fig. 13, against the compression of the spring 478 until the plate is free of the recess 480, when it may be rotated at will in a counterclockwise direction.

As pointed out above, dimensions of various soles for the same class of shoes vary substan-

tially proportionally irrespective of the size of the soles. It is apparent, then, that for soles of the same class of shoes the ratio of the width extension to the length extension between soles of various sizes is substantially constant. In order that the sole may be gaged both lengthwise and widthwise thereof simultaneously, the gage body 456 is mounted on a pin 482 having a T-shaped head which engages and slides in a slideway 484 the angle of which with respect to the axis of the sole is such that, when the gage body 456 is moved longitudinally to accommodate a change in length of soles, the abutment 460 is also moved widthwise of the sole an amount equal to the corresponding change in width. The slideway 484 is properly adjusted when the tangent of the angle between its axis and the axis of the sole is equal to the ratio of the width extension to the length extension of soles of the same class but of varying sizes. The adjustment of the slideway 484 is provided by pivotally mounting it at one end by a pin 486 on a support 488 which is pinned to the rod 314, thereby holding it against longitudinal movement. The slideway 484 is clamped at the end opposite from its pivotal connection with the support 488 by means of a screw 489 which is threaded into a clamp 491 having a hooked end which engages the lower arcuate marginal end of the support 488. The support also engages 105 at its lower end a rod 490 supported at either end by extensions 492 to the legs 218 of the fore part clamping table.

In the case when the work being operated upon requires the clamping mechanisms to be 110 relatively displaced, and the fore part clamping mechanism is moved lengthwise of the sole, the fore part clamping table slides along the rod 314, the rod being prevented from moving axially; and the rod 490 which connects the extensions 492 on the legs 218 of the fore part clamping table slides in a complementary hole in the lower end of the support 488. It is therefore evident that a relative displacement occurs 115 between the fore part clamping table and the corresponding gage mechanism when the fore and heel part clamping mechanisms are relatively displaced. This relative movement, however, occurs when the work is in clamped position, in which position the rubber tubing abutment 460 is disposed between the clamping elements; but on account of the gage being constructed to collapse as it is clamped, it is not gripped so firmly that it cannot slip between the clamping elements as they are displaced with 120 respect to the gage mechanism which, therefore, is not strained. The gage body 456 is operated and maintained in a position of axial alinement with the pattern by a square rod 494 engaging a complementary recess therein. The rod 494 is rotatably carried by a stud 496 firmly fixed by means of a nut 498 to the end of a rock lever 500 which is pivotally mounted at its mid portion to the support 488 by a bolt 502 (Fig. 4). A roll 504 is rotatably mounted on the 125 end of the rock lever 500 and is adapted to engage either side of a fork 506 (Fig. 1) slidably supported at its vertex 508 on a rod 510 and at the bifurcated ends 512 by a rod 514, both of which rods are supported at their ends by the sides of the upper frame and at their mid portions by the central web thereof. As indicated in Fig. 1, the roll 504 on the end of the rock lever engages that side of the fork to which it 130

135

140

145

150

is nearer when the clamping table, which indirectly supports the rock lever, is swung out to the blank receiving position and in which position the roll 504 is in contact with both sides of the fork 506. The position of the fork 506 along the supporting rods 510 and 512 determines the position in which the gage for the sole blank shall be moved when the clamping tables are rotated to their blank receiving position. The heel part clamping mechanism is also provided with a gage mechanism similar to that already described as used in connection with the fore part mechanism. However, since there is no lateral displacement of the heel part clamping mechanism with respect to the frame, the gaging mechanism thereof may be mounted directly on the heel part clamping table and is otherwise substantially a duplicate of the fore part gaging mechanism except that the width abutment of the heel part, and the gage 516 for the end of the sole are not pivoted but are effectually integral with the body. The heel part gaging mechanism is operated by a rock lever 518 which is pivoted at its center to an extension 520 of a heel part clamping table leg by means of a stud 522 (Fig. 6). A roll 524 on the lower end of the rock lever 518 is adapted to engage a fork 526 supported by the rods 510 and 512 in a manner similar to that in which the fork 506 is supported. It is apparent from Fig. 1 that the positions of the respective gages on the heel and fore part clamping mechanism are altered to accommodate a larger or smaller sole by movements in opposite directions, and hence the forks 506 and 526 must be moved in opposite directions. To this end racks 528 and 530 are attached to the vertices of the fore and heel part gaging forks, respectively (Figs. 1 and 2), and mesh with gears 532 and 534, respectively, which are keyed to a shaft 536, to the outer end of which is fixed the lower end of a control lever 538. The shaft 536 and the gears 532 and 534 are housed in a casing 540 attached to the front portion of the central web 40 of the upper frame 42. By rotating the gears 532 and 534 by means of the control lever 538, the racks 528 and 530 are moved in opposite directions inasmuch as they mesh at opposite sides of the axis of the driving gears. It may be further noted that the gear 534 is smaller than the gear 532 by an amount proportional to the difference between the increase in width in the fore and heel parts of soles of consecutive sizes but of the same class.

The control lever 538 may be moved at any stage of the operation of the machine but acts directly to adjust the gage mechanism only when the clamping mechanism carrying the gage mechanism to be so adjusted has been swung to its blank receiving position in which the rolls 504 and 524 on the lower end of the rock levers 518 are at the lowermost part of the forks 506 and 526. Then, a movement of the control lever in either direction will result in a corresponding movement of the gages with no lost motion. If the control lever is moved to the desired position, to gage a sole of a different size from that previously operated upon, before the clamping mechanism is swung out far enough to become engaged with either side of the fork, the gages are not operated until the rolls on the rock levers engage whichever side of the forks they are nearer. As the clamping mechanisms continue to swing to their blank

receiving position, the gages are operated by the rock arms, the rolls on which follow the inclination of whichever side of the forks they are in contact. Thus, it is apparent that the setting of the gage mechanism for a sole of a size different from that which is being operated upon will automatically set the gage mechanism of the latter instrumentality when it has been swung to its blank receiving position.

80

In order that the operator of the machine may easily adjust the control lever 538 to the proper position to gage the soles upon which a shaping operation is to be performed, a scaling device is provided from which the proper position of the lever 538 may be determined in order to gage correctly any style and any size of sole of the styles for which the scales are calibrated. To this end a style scale 542 (Fig. 15), a width scale 544 and a length scale 546 are secured to the central portion of a table 548, the width and length scales being constructed for longitudinal adjustment. In using the scaling device, the width scale is moved so that its index is opposite the graduation on the style scale which indicates the style of sole to be operated upon and is then firmly clamped to the table by means of a screw 550. The length scale is next to be moved so that its index is opposite that graduation on the width scale corresponding to the width of the soles to be operated upon and is then clamped to the table by a screw 552. The operator then grasps the knob 544 on the end of the control lever 538 and moves it until its index 556 lies opposite to that graduation which corresponds to the length of the sole being operated upon. Soles of the same style and width size may thus be grouped for the sake of convenience and economy and operated upon in the machine with the scales maintained in one setting, variations of length being accommodated by moving the index on the lever 538 to the graduation corresponding to the length of the sole to be operated upon. If it is desired, the positions of the width and length scales may be interchanged, in which case soles of the same style and length size but of different width sizes may be operated upon in the machine while the scales are maintained at the same setting.

85

The lengths and widths of soles of radically differing styles, such for example as children's, women's and men's, may differ appreciably, and if soles of such a group of classes are to be treated in a factory in which the illustrated machine is to be used, the scale arrangement shown in Fig. 15 is inadequate and a scale arrangement such as is illustrated in Fig. 16 is used. This scaling device comprises a style scale 558 having as many sets of style graduations as classes of soles commonly treated in the machine. This scale is fixed to the table 135 548. The width scale 560 is adjustably secured to the base of the table 548 and has a set of graduations corresponding to each set of style graduations on the scale 558. A length scale 562 is also adjustably secured to the table and has two slightly separated ears 564 extending from its edge adjacent to the width scale. The purpose of these ears is to obscure all of the graduations on the width scale except those that are in the set of graduations on the width scale 140 which correspond to the style graduations against which the index 566 on the width scale has been adjusted. Thus it is apparent that when the scales are being adjusted there can be no question in the mind of the operator as 145 150

to which set of width graduations are to be used in connection with any set of style graduations. The scale device illustrated in Fig. 16 is adjusted in the following manner: The width scale 560 is so moved that its index 566 is placed opposite to the desired style graduation and it may then be clamped in position by means of a screw 568. The length scale 562 is next moved so that its index 570 is opposite the desired width graduation on the width scale, and the length scale is then clamped by means of a clamping screw 572. The gages on the machine may then be adjusted as above described by moving the knob 544 so that its index 556 is opposite the graduation on the length scale corresponding to the length of the sole to be treated.

When either of the scaling devices described above is employed, only those soles which are either of the same width size or of the same length size may be operated upon consecutively without resetting the scales. In order to obtain the advantages of the scaling device as illustrated in Fig. 16, and also to make it possible to gage all the soles of the same style irrespective of their width or length with one setting of the scaling device, that shown in Fig. 17 has been evolved. This device comprises a style scale 574 which is fixed to the table 548. An adjustable length scale 576 is secured to the table by means of a thumb screw and kerfed screw 578 and 580, respectively. The width scale 582 is triangular in cross-section, furnishing three faces upon which a like number of sets of width graduations may be impressed. The width scale is pivotally mounted between lugs 584 which are fixed to the upper end of the arm 538. At each vertex on one end of the width scale is a protrusion 586 which is adapted to fit within a slot (not shown) on the inner side of one lug 584 in order that the width scale desired to be used may be held in an uppermost position. When a scale such as has just been described is used in the illustrated machine, the length scale 576 is moved and clamped so that its index 588 is opposite the style graduation corresponding to the style of the sole to be operated upon and the control lever 538 is moved to that position in which the graduation on the width scale corresponding to the width of the sole to be operated upon is opposite to the graduation on the length scale indicating the length of the sole to be operated upon. It is apparent that with one setting of the length scale, as illustrated in Fig. 17, corresponding to the style of sole to be operated upon, all soles of that style irrespective of their width or length may be gaged in the machine by only the proper manipulation of the control lever 538.

In order to protect the mechanism for operating the clamping tables, a guard (not shown) may be provided. The guard, as used in the illustrated machine, is arcuate in shape and is supported at its upper edge by a pin 590 which is fixed in an upstanding lug 592 in the fore part clamping table 22. The guard is guided at one end and centrally of the machine in a guideway 594 and at the outer side of the machine by an abutment 596, and is moved back and forth in its guideways as the clamping tables are swung back and forth between the clamping and blank receiving positions by the pin 590 which moves with the fore part clamping table.

To prepare the illustrated machine for operating upon soles in the manner hereinbefore described, a pattern corresponding to the type

of work to be operated upon is selected and the relative displacement of the fore and heel part clamping mechanisms is so adjusted that the dowels 26 will fit into the recess in the bottom of the pattern. The pattern is then seated on the clamping tables. The scale arrangement is next properly adjusted for the particular type of work to be operated upon and the control lever 538 is moved so that its index is opposite that graduation of the adjacent scale corresponding to the size of the sole to be operated upon. For convenience of description, let it be assumed that the parts of the machine are in the position indicated by Fig. 1. The clamping table in the right-hand side of the machine is now ready to receive a blank and the operator places a sole blank on the pattern so that the toe is in abutting relation with the finger 450 (Fig. 13) and the sides of the fore and heel parts abut the respective gages for positioning the soles widthwise of the pattern. The operator then depresses the treadle 166, connecting the source of power to the cam shaft 123 through the clutch and gear drive which has been described above. The clamping mechanism on which the sole blank has just been placed is swung to its vertical position in which position the clamping table is raised with respect to the clamping jaws firmly to grip the work therebetween. Further rotation of the cam shaft 123 will cause the cams 282 to operate the conforming mechanism, which forces the shank portion of the sole blank against and about the corresponding part of the pattern. As the conforming tool is retracted from the work, the clamping mechanism lowers the clamping table with respect to the clamping jaws and, as soon as their relative movement has ceased, the clamping table is swung outwardly again to blank receiving position in which position the operator removes the sole which has just been treated and places a fresh blank on the pattern. The above description refers only to one cycle of operation of one side of the machine when a pattern such as that shown in Fig. 1 or Fig. 14 is used. It is to be understood, however, that, during the time in which the operator is removing a treated sole from the pattern and replacing it with a fresh blank, the shank treating operation is being effected by the conforming mechanism in the other side of the machine. One clamping table is in the blank receiving position during substantially the same time in which the other is in the vertical position in which the sole is clamped and operated upon, and, similarly, while one clamping table is swung from the blank receiving position to the clamping and operating position, the other clamping table is swung from the clamping and operating position to its blank receiving position. When the machine is used for operating upon soles for which a pattern such as that shown in Fig. 9 is used, the operation of the machine is like that above described except that the heel clamping mechanism is dropped relatively to the fore part clamping mechanism in order to produce a sole the shank of which is disposed obliquely to the fore part. As above stated, whether the distance between the fore and heel part clamps is to be held constant, increased or decreased upon their relative displacement is dependent upon the position of the universal connection 364. That is, if the universal connection is in the center of the slot 366, there is no relative dis-

- placement longitudinally of the sole of the clamping mechanisms; the extent to which the clamping mechanisms are separated upon their displacement may be varied by adjusting the universal connection above its central position in the slot 366; and similarly, the extent to which the distance between the clamping mechanisms may be decreased may be varied by adjusting the universal connection 364 in the lower portion of the slot 366. The heel dropping operation occurs substantially simultaneously with the operation of the conforming mechanism to force the shank of the sole blank about the corresponding part of the pattern.
- 15 Accordingly, the conforming tool is lowered simultaneously with the heel part of the pattern but at a slightly higher rate, depending upon the amount of clearance between the shank portion of the sole and the conforming tool
- 20 before the heel dropping operation has commenced.

Having described my invention, what I claim as new and desire to secure by Letters Patent of the United States is:—

- 25 1. That method of treating soles which consists in stretching the shank portion by increasing amounts across part of the width of the shank and at either side of its central longitudinal axis, and by substantially equal amounts outwardly across the remainder of the shank at either side of its longitudinal axis.
2. That method of treating soles which consists in controlling the relative position of the forepart and heel part of the sole and while thus controlling them stretching the shank portion lengthwise thereof throughout its heightwise extent at either side of its central longitudinal axis without stressing the axial portion lengthwise thereof.
3. That method of treating soles which consists in constraining the fore part and heel part of the sole against relative lengthwise movement, disposing the fore part and heel part obliquely to the shank portion, and imparting a transverse curvature to the central portion of the shank without extending it.
4. That method of treating soles which consists in constraining the fore part and heel part of the sole against relative lengthwise movement, disposing them obliquely to the shank portion, and imparting a transverse curvature continuous between the fore and heel parts to the central portion of the shank.
5. That method of treating soles which consists in bending and holding the fore part and heel part in positions oblique to the shank portion, and stretching the shank portion by increasing amounts across part of its width and at either side of its central longitudinal axis and by substantially equal amounts outwardly across the remainder of the shank at either side of its longitudinal axis.
6. That method of treating soles which consists in restraining movement of the fore part and heel part while held obliquely to the shank portion, stretching the marginal portion of the shank uniformly, and stretching successive increments of width at either side of the center of the shank by increasing amounts.
7. That method of treating soles which consists in tempering the sole to be operated upon, controlling the relative position of the forepart and heel part and while thus controlling the forepart and heel part stretching the shank portion lengthwise thereof throughout its height-

wise extent at either side of its central longitudinal axis without stressing the axial portion lengthwise thereof.

8. That method of treating soles which consists in tempering the sole to be operated upon, constraining the fore and heel parts against relative longitudinal movement, disposing them obliquely to the shank portion, stretching the marginal portions of the shank uniformly, and stretching successive increments of width at either side of the center thereof by increasing amounts.

9. That method of treating soles which consists in tempering the sole to be operated upon, disposing the fore and heel parts obliquely to the shank portion, stretching the marginal portions of the shank uniformly, and stretching successive increments of width at either side of the center to said marginal portions thereof by increasing amounts.

10. That method of treating soles which consists in tempering the sole to be operated upon, and stretching the shank portion by increasing amounts at either side of its center to produce a transverse curvature therein continuous between the fore and heel parts, and stretching the shank uniformly across a relatively narrow marginal portion to insure against splitting or cracking the edge of the shank.

11. In a machine for shaping soles, means for clamping the fore and heel parts of a sole, a pattern for shaping the shank portion thereof and means for holding the shank of the sole against the pattern whereby a transverse curvature is imparted only to the central portion of the shank.

12. In a machine for shaping soles, means for clamping the fore and heel parts of a sole, a pattern for shaping the shank portion of the sole, and means for holding the shank of the sole against said pattern to impart a continuous transverse curvature to the shank, said pattern being constructed and arranged to support the axial portion of said shank thereby to prevent lengthening of the sole during the shaping operation.

13. In a machine for shaping soles, means for disposing the fore and heel parts obliquely to the shank portion, and means for imparting a transverse curvature to only the central portion of the shank.

14. In a machine for shaping soles, means for constraining the fore and heel parts of a sole against relative longitudinal movement and disposing them obliquely to the shank portion, and means for stretching the shank lengthwise at either side of the central longitudinal axis without stressing the axial portion thereof.

15. In a machine for shaping soles, a pattern, and means cooperating therewith to stretch the shank portion of a sole by increasing amounts across part of the width of the shank and at either side of its central longitudinal axis and by substantially equal amounts outwardly across the remainder of the shank at either side of its longitudinal axis.

16. In a machine for shaping soles, means for disposing the fore and heel parts obliquely to the shank portion, a pattern, and means cooperating therewith to stretch the shank portion of a sole by increasing amounts across part of the width of the shank and at either side of its central longitudinal axis and by substantially equal amounts outwardly across the remainder

- of the shank at either side of its longitudinal axis.
17. In a machine for shaping soles, means for clamping the fore and heel parts of a sole, means for displacing the heel part clamp relatively to the fore part clamp, a pattern, and means cooperating therewith to stretch the shank portion of the sole by increasing amounts across part of the width of the shank and at either side of its central longitudinal axis and by substantially equal amounts outwardly across the remainder of the shank at either side of its longitudinal axis. 80
18. In a machine for shaping soles, means for clamping the fore and heel parts of a sole, means for relatively displacing said clamps whereby the shank portion is disposed obliquely to the fore and heel parts, a pattern, and means cooperating therewith to stretch the shank portion of the sole by increasing amounts across part of the width of the shank and at either side of its central longitudinal axis and by substantially equal amounts outwardly across the remainder of the shank at either side of its longitudinal axis. 85
19. In a machine for shaping soles, means for clamping the fore and heel part portions of a sole, a pattern for shaping the shank disposed between said clamps, and means cooperating with the pattern to hold the shank about the pattern whereby the shank portion is stretched by increasing amounts at either side of the center to produce a transverse curvature therein continuous between the fore and heel parts and uniformly across a relatively narrow marginal portion to insure against splitting or cracking of the edge of the shank. 90
20. In a machine for shaping soles, clamping means for disposing the fore and heel parts obliquely to the shank portion, a pattern supported by said means, and means cooperating with the pattern to stretch the shank portion of a sole by increasing amounts across part of the width of the shank and at either side of its central longitudinal axis and by substantially equal amounts outwardly across the remainder of the shank at either side of its longitudinal axis. 95
21. In a machine for shaping soles, means for displacing the heel part clamp relatively to the fore part clamp, a pattern supported by said clamping means, and means cooperating with the pattern to stretch the shank portion of the sole by increasing amounts across part of the width of the shank and at either side of its central longitudinal axis and by substantially equal amounts outwardly across the remainder of the shank at either side of its longitudinal axis. 100
22. In a machine for shaping soles, means for relatively displacing said clamps whereby the shank portion is disposed obliquely to the fore and heel part portions, a pattern supported by said clamping means, and means cooperating therewith to stretch the shank portion of the sole by increasing amounts across part of the width of the shank and at either side of its central longitudinal axis and by substantially equal amounts outwardly across the remainder of the shank at either side of its longitudinal axis. 105
23. In a machine for treating soles, a pattern for forming the shank portion of a sole having a convex work engaging face bordered by a surface substantially parallel to a surface tangent to the convex face of the pattern. 110
24. In a machine for treating soles, means for clamping the fore and heel parts of a sole, means for relatively displacing the clamps in a direction perpendicular to the plane of the clamping faces, and a pattern comprising a shank element extending between the fore and heel part elements and pivotally connected to one of them. 115
25. In a machine for operating upon soles, plural means for clamping the fore and heel parts of a sole mounted for movements relatively to each other in mutually transverse directions, and means for imparting said relative movements to said clamping means simultaneously and in predetermined timed relation to each other. 120
26. In a machine for operating upon soles, means for clamping the fore and heel parts of a sole mounted for movements relatively to each other in mutually transverse directions, means for relatively moving said clamping means in one direction, and means operated by the relative movement of the clamping means in the said one direction for moving them relatively to each other in the other direction. 125
27. In a machine for operating upon soles, means for clamping the fore and heel parts of a sole mounted for movements relatively to each other in different directions, means for moving the fore and heel part clamping means relatively to each other in one direction in order to make the angular relation between the shank and the fore and heel parts the same as it is to be in the finished shoe, and means connecting said fore and heel part clamping means operated by the above-mentioned relative movement to cause them to be relatively moved in the other direction. 130
28. In a machine for operating upon soles, means for clamping the fore and heel parts of a sole, each of said clamping means being mounted for movement in a direction transverse to the movement of the other, means for moving said heel part clamping means relatively to the fore-part clamping means to give the shank of the sole and the fore and heel parts such an angular relation as they are to have in the finished shoe, and means connecting the clamping means for moving the forepart clamping means a predetermined amount relatively to the heel part clamping means. 135
29. In a machine for operating upon soles, means for clamping the fore and heel parts of a sole mounted for movements in paths transverse to each other, means for moving the heel part clamping means relatively to the forepart clamping means to make the angular relation between the shank and the clamped parts the same as it is to be in the finished shoe, and connections between the fore and heel part clamping means constructed and arranged to move the forepart clamping means toward the path of the heel part clamping means as the latter is moved. 140
30. In a machine for operating upon soles, means for clamping the fore and heel parts of a sole, each of said clamping means being mounted for movement in a path extending transversely of the path of the other, means for moving the heel part clamping means relatively to the forepart clamping means to give the shank of the sole and the fore and heel parts such an angular relation as they are to have in the finished shoe, and connections between the clamping means operated by the movement of said heel part clamping means for moving the forepart clamping 145
- 75 to the convex face of the pattern. 150

means toward the path of the heel part clamping means as the latter is moved.

31. In a machine for operating upon soles, means for clamping the fore and heel parts of a sole mounted for movement relatively to each other in mutually transverse directions, means for relatively moving the clamping means in one direction to give the shank of the sole and the fore and heel parts such an angular relation as 10 they are to have in the finished shoe, and a link connecting said clamping means and operated by the relative movement of the clamping means in the said one direction for moving them relatively in the other direction.
32. In a machine for operating upon soles, means for clamping the fore and heel parts of a sole each of which is mounted for movement in a path which extends transversely of the path of the other, and means for controlling the relative 20 movement of said clamping means comprising a link mounted with respect to said heel part clamping means for adjustment in a direction transverse to the path of movement of the fore-part clamping means.

33. In a machine for operating upon soles, means for clamping the fore and heel parts of a sole, each of said clamping means being mounted for movement extending transversely of the path of the other, a link pivotally connecting said fore and heel part clamping means and mounted for adjustment with respect to the heel part clamping means transversely with respect to the path of movement of the forepart clamping means, and means for relatively moving the clamping means so as to give the shank the same relation to the fore and heel parts of the sole as it is to have in the finished shoe.
34. In a machine for operating upon soles, means for clamping the fore and heel parts of the sole, each of said clamping means being mounted for movement in a path extending transversely to the path of the other, a link one end of which is mounted for adjustment with respect to the forepart clamping means in the direction of its 40 movement and the other end of which is mounted for adjustment with respect to the heel part clamping means in substantially its direction of movement with respect to the forepart clamping means, and means for moving said clamping 50 means relatively to each other so as to give the shank the same angular relation with respect to the fore and heel parts as it is to have in the finished shoe.

35. In a machine for treating soles, means for 55 clamping the fore part of a sole, means for clamping the heel part, and means for relatively displacing said means by rotation while they are maintained in parallelism and while clamping the sole.

36. In a machine for treating soles, means for 60 clamping the fore part of a sole, means for clamping the heel part, and means for relatively displacing said means while maintaining them in parallelism by relative rotation about a plurality of axes while in clamped position.

37. In a machine for treating soles, means for 65 clamping the fore part of a sole, means for clamping the heel part, and means for relatively displacing said clamping means in parallelism 70 by rotation about a plurality of axes simultaneously while clamping a sole.

38. In a machine for treating soles, means for 75 clamping the fore part of a sole, means for clamping the heel part, and means for relatively displacing said means in parallelism by relative

rotation about two axes parallel and perpendicular, respectively, to the direction of motion of the heel part clamp.

39. In a machine for treating soles, means 80 for clamping the fore part of a sole, means for clamping the heel part, and means for relatively displacing said means in parallelism by relative rotation about two mutually perpendicular axes.

40. In a machine for treating soles, means for clamping the heel part of a sole, and an adjustable clamp for the fore part thereof constructed and arranged to be swung about an axis perpendicular to its work engaging face to accommodate various lengths of soles.

41. In a machine for treating soles, means for clamping the heel part of a sole, and an adjustable clamp for the fore part thereof constructed and arranged to be swung about an axis perpendicular to its work engaging face and to be held in a relation of parallelism to the heel part clamp throughout the range of its adjustability.

42. In a machine for treating soles, means for clamping the fore part of a sole, means for clamping the heel part of the sole, and means 100 connecting said clamps whereby the distance therebetween may be increased, held constant or decreased as the heel part clamp is displaced in a direction substantially perpendicular to the face of the fore part clamp.

43. In a machine for treating soles, means for clamping the fore part of a sole, means for clamping the heel part of the sole, and means connecting said clamps whereby the distance therebetween may be increased, held constant, or decreased as the heel part clamp is displaced from a position of alignment with the fore part clamp in a direction substantially perpendicular to the face of the fore part clamp.

44. In a machine for treating soles, means for clamping the fore and heel parts of a sole, said means being relatively rotatable in the plane of the sole, and means for adjustably limiting the distance between said clamping means in accordance with the length of the sole to be operated upon.

45. In a machine for treating soles, means for clamping the fore and heel part of a sole, means for relatively displacing said clamping means, 125 and means adjustably connected to each of said clamps for limiting the distance therebetween as they are displaced.

46. In a machine for treating soles, means for clamping the fore and heel parts of a sole, said 130 clamping means being relatively rotatable in the plane of the sole, and relatively movable in parallelism to cause the shank portion of the sole to be angularly disposed with respect to the fore and heel parts thereof, and means for controlling both of the above-mentioned relative movements adjustably connecting said fore and heel part clamping means.

47. In a machine for shaping soles, a shaping tool comprising a body portion having an abutment, a conforming element, resilient means arranged to hold said conforming tool in engagement with said abutment, and means pivotally connecting said body portion and said conforming element.

48. In a machine for shaping soles, a shaping tool comprising a body portion and a conforming element arranged to rock about a fulcrum on said body portion, means for yieldingly holding said conforming element against said ful-

- crum, and means pivoted to said body portion pivotally supporting said conforming element.
49. In a machine for shaping soles, a shaping tool comprising a body portion and a conforming element arranged to rock about a fulcrum on said body portion, and means connecting said body portion and said conforming tool allowing a pivotal movement of the latter about axes at opposite sides of said fulcrum.
50. In a machine for shaping soles, a shaping tool comprising a body portion and a conforming element arranged to rock about a fulcrum on said body portion, and a link pivoted at one side of said fulcrum to said body portion arranged to support said conforming element for pivotal movement about an axis on the opposite side of said fulcrum.
51. In a machine for shaping soles, a pattern, a conforming tool, and means for operating the conforming tool to force the shank of a sole on the pattern thereagainst, said conforming tool comprising a work engaging element rotatable about a plurality of axes whereby the work engaging face of the conforming tool may be disposed squarely against the shank of the sole.
52. In a machine for shaping soles, a pattern, a conforming tool for holding the shank of a sole against the pattern comprising a body portion, a link pivoted thereto at one end, and a work engaging portion pivoted to the other end of the link constructed and arranged resiliently to be held against the body portion.
53. In a machine for treating soles the width and length of which vary proportionally between the sizes, a pattern, means for moving said pattern alternately between a sole receiving and operating position, a gage mounted for movement in a direction at an angle to the axis of the pattern the tangent of which is equal to the ratio of the increase in width to the increase in length between successive sizes of soles, and means for controlling the movement of said gage arranged to be operated when the pattern is moved to the sole receiving position.
54. In a machine for operating on soles, a pattern for shaping the shank of a sole, and means for positioning the sole on the pattern comprising abutments adapted for contact with the edge of the sole at an end and at special points at one side thereof thereby to locate the sole laterally and longitudinally, said means being mounted for rectilinear adjustment to aline laterally and longitudinally with respect to the pattern different sizes of soles of one style.
55. In a machine for operating on soles, a pattern for shaping the shank of a sole, and a gage for positioning the sole on the pattern mounted to slide obliquely with respect to the longitudinal axis of said pattern in order simultaneously to aline laterally and longitudinally with respect to the pattern different sizes of soles of one style.
56. In a machine for operating on soles, a pattern for shaping the shank of a sole, and means for positioning the sole on the pattern comprising abutments arranged to engage the edge of the sole thereby to limit its movement with respect to the pattern, said means being mounted for rectilinear adjustment in a direction oblique to the longitudinal axis of the sole whereby widthwise and longitudinal positioning of a sole on the pattern is effected by one adjustment of said means.
57. In a machine for operating upon soles, a pattern for shaping a sole, means for alining a sole laterally and longitudinally with respect to the pattern having abutments adapted respectively to engage the sole edge at an end and side, a slideway supporting the last-mentioned means and mounted for angular adjustment with respect to the pattern whereby the said last-mentioned means can be moved in one direction simultaneously to position soles of different sizes both laterally and longitudinally with respect to the pattern.
58. In a machine for treating soles of the same length size but of different width sizes, a pattern for shaping the shank portions thereof, means for gaging the position of said soles on the pattern by contact with the side and end portions of the sole, said means being constructed and arranged to compensate for the length extension simultaneously with the change in width.
59. In a machine for treating soles of the same width size but of different length sizes, a pattern for shaping the shank portions thereof, means for gaging the position of said soles on the pattern by contact with the sides of the fore and heel part portions and one end of the soles, said means being constructed and arranged to compensate for the width extension simultaneously with the change in length.
60. In a machine for shaping soles, a pattern, a clamp, means for moving said clamp toward and away from said pattern successively to hold and release a sole on said pattern, and means for swinging said pattern laterally of said clamp after the sole is released to facilitate the removal of the sole from the pattern.
61. In a machine for shaping soles, a pattern, means for clamping the fore and heel parts of a sole on said pattern, a tool arranged to engage the shank of the sole and to hold it against the pattern thereby to shape the shank, means for operating said clamping means and shank shaping tool in succession, and means operated in alternation with the movement of both the clamp and tool operating means for swinging said pattern successively away from and toward said clamp to facilitate the interchange of an unshaped sole for that last operated upon.
62. In a machine for shaping soles, relatively movable means for clamping a sole, a pattern on said clamping means, means for rotating said clamping means to facilitate placing the sole thereon, and a gage for positioning the sole on the pattern actuated as said clamping means is rotated to sole receiving position.
63. In a machine for shaping soles, a pattern and means for clamping a sole against said pattern constructed and arranged for relative translation to clamp the work and for relative rotation to facilitate placing the sole on the pattern, and a gage for positioning the sole on the pattern operated by the rotation of the clamping means.
64. In a machine for operating on soles, means for clamping a sole, means for positioning a sole on said clamping means comprising an abutment having a flexible work engaging element, and means constructed and arranged normally to tension said element heightwise of the sole to cause it to present a flat gaging surface to the sole edge.
65. In a machine for operating on soles, means for clamping a sole, and a gage for positioning a sole on said clamping means having a flexible work engaging element and means engaging op-

posite sides of said element constructed and arranged to tension it heightwise of the sole to provide a relatively flat gaging surface.

66. In a machine for operating upon soles, means for clamping a sole, means for gaging the sole on said clamps comprising a flexible tubular abutment, and resilient means constructed and arranged normally to flatten said abutment heightwise of the sole to provide a relatively flat gaging surface for the edge face of the sole.

67. In a machine for operating upon soles, alternately operable means for clamping soles to be treated, each means comprising a table mounted to swing into and out of operative relation to a clamping member, gaging means on each of said tables for locating a sole thereon, each of said gaging means being constructed and arranged to be adjusted to locate a different size of sole only when its associated table is swung into inoperative position.

68. In a machine for operating on soles, means for clamping soles to be treated constructed and arranged to be swung alternately between receiving and treating positions, gages associated with each of said clamping means arranged to be adjusted for positioning the soles thereon in the receiving position, and means for adjusting each of said gages for a given sole size when the other clamping means is swung into the treating position.

69. In a machine for operating on soles, means for clamping soles to be treated constructed and arranged to be swung alternately between a receiving and treating position, means associated with each of said clamping means for accurately positioning the soles thereon irrespective of their size, and means for setting each of said positioning means only while its associated clamping means is in receiving position.

70. In a machine for treating soles, sole clamping means, sole supporting means, means for causing a relative translation of the clamping and supporting means to clamp a sole and a relative rotation to facilitate the removal of the sole, gages on the sole supporting means, and gage setting means which is arranged to operate the gages as the sole supporting means

is rotated out of operative relation with the clamping means.

71. In a machine for treating soles, sole clamping means, a pair of sole supporting means movable alternately into and out of operative relation to the clamping means, gages on each of the sole supporting means, and gage setting means for each of the gages which is in operative relation to the gages only when its sole supporting means has been moved out of operative relation to its clamping means and is then operative to set the gages of its sole supporting means and to set the setting means for the gages of the other sole supporting means.

72. In a machine for treating soles, the combination of clamping means, sole supporting tables co-operating with the clamping means and movable alternately into and out of operative relation to the clamping means, gaging means upon each of the tables for similarly locating soles of various sizes, gage setting means for each gaging means, and means for operating all of the gage setting means simultaneously, movement of either table out of operative relation to the clamping means causing the gage setting means to set the gages of that table.

73. In a machine for treating soles, the combination of clamping means, sole supporting tables co-operating with the clamping means and movable alternately into and out of operative relation to the clamping means, gages upon each of the tables for similarly locating soles of various sizes, gage setting mechanism for each gaging means, means for operating the gage setting mechanism of the table which is out of operative relation to the clamping means to set the gages of that table for a sole of a given size, and connections between the gage setting mechanisms for causing the gage setting mechanism of the table which is in operative relation to the clamping means to be similarly set so that upon movement of that table out of operative relation to the clamping means its gages will be set for a sole of the same size as that for which the gages of the other table were set.

CERTIFICATE OF CORRECTION.

Patent No. 1,939,750.

December 19, 1933.

ERASTUS E. WINKLEY.

It is hereby certified that error appears in the printed specification of the above numbered patent requiring correction as follows: Page 1, line 10, for "shoes" read shoe; page 4, line 48, for "4" read 42; page 8, line 127, for "9" read 12; page 9, line 31, for "sole" read soles; and line 55, for "place" read plate; and page 15, line 46, claim 54, for "shapping" read shaping; and line 49, same claim, for "special" read spaced; and that the said Letters Patent should be read with these corrections therein that the same may conform to the record of the case in the Patent Office.

Signed and sealed this 3rd day of April, A. D. 1934.

F. M. Hopkins

(Seal)

Acting Commissioner of Patents.
